UNITED STATES PATENT OFFICE.

JOHN HAHN, OF LOS ANGELES, CALIFORNIA.

DEEP-WELL PUMP.

1,378,949.

Specification of Letters Patent. Patented May 24, 1921.

Application filed April 1, 1919. Serial No. 286,681.

To all whom it may concern:

Be it known that I, JOHN HAHN, a citizen of the United States, residing at Los Angeles, in the county of Los Angeles and State of California, have invented a new and useful Deep-Well Pump, of which the following is a specification.

This invention pertains to pumps used in pumping liquids from wells, and is especially suited to working in comparatively deep wells for pumping oil therefrom.

An object of the invention is to so construct the pump that the gas in the oil well will not interfere with the efficient action of the pump.

Another object is to so construct the pump that sanding thereof will not be liable.

In some of the California oil wells, not only is great depth of the well attained in many instances, but a large amount of sand must be contended with in the pumping operation. Oil wells produce more or less natural gas and this gas interferes with the closing of the valves in the pumps heretofore in use, so that on the delivery stroke of the pump much of the oil that would be delivered, if the valves would properly seat, is allowed to escape past the plunger and therefore for the maximum efficiency of the pump is not attained.

Another object is to provide a construction whereby the conduit is detachably seated and may be readily withdrawn from the well with the plunger.

Another object is to make provision for the entrance of oil to the plunger above the standing valve on the upstroke of the plunger so as to hold the standing valve closed and submerge the standing valves and lower plunger valve in the liquid being pumped.

Other objects and advantages will appear in the subjoined detailed description.

The accompanying drawings illustrate the invention:

Figure 1 is a side elevation, partly in vertical mid section of a pump constructed in accordance with the provisions of this invention, a portion of the sand trap being broken away to contract the view.

Fig. 2 is an enlarged sectional elevation of the upper portion of the pump shown in Fig. 1.

Fig. 3 is an enlarged sectional elevation of the intermediate portion of the pump.

Fig. 4 is an enlarged sectional elevation of the lower portion of the pump.

Fig. 5 is a plan section on line indicated by x^5-x^5 , Fig. 2.

Fig. 6 is a plan section on line indicated by x^6-x^6 , Fig. 3.

Fig. 7 is an enlarged sectional elevation of the upper portion of Fig. 2.

Fig. 8 is an inverted plan section on line indicated by x^8-x^8 , Fig. 7.

Fig. 9 is a plan section on line indicated by x^9-x^9 , Fig. 7.

Fig. 10 is a side elevation of the upper plunger barrel or guide.

Fig. 11 is an enlarged sectional elevation of the upper portion of Fig. 4.

Fig. 12 is a plan section on line indicated by $x^{12}-x^{12}$, Fig. 11.

There is provided a lower seat member 1 having a downwardly and inwardly tapered seat 2 to receive and frictionally hold a seat member in the form of a downwardly and inwardly tapered solid plug 3 which is preferably of non-magnetizable metal and which is screw-threaded into the lower end of an inner sand trap tube 4 extending through and spaced from an external sand trap tube 5 that in turn is screw-threaded at its lower end into the seat member 1 above the seat 2. The lower end of the seat member 1, if desired, may be provided with internal screw-threads 6 adapted to engage the upper end of a tube catcher, not shown, of any suitable construction. The seat member 1, plug 3 and tubes 4 and 5 constitute a sand trap, and the inner trap tube 4 is provided with perforations 7 to afford communication between the inner and outer tubes so that sand and liquid may pass into the outer tube.

The upper end of the tube 5 is screw-threaded into a seat member 8 which is provided with a downwardly and inwardly tapered seat 9 adapted to fit a downwardly and inwardly tapered annular seat member 10 that slidably fits on a perforated lower conduit tube 11, said perforations or ports 100 being indicated at 12. The upper end of the tube 11 is screw-threaded into, or otherwise attached to, a lower valve cage 13 provided with the usual ball valve 14 and seat 14' to control the flow of liquid upward through said valve cage. The cage 13, ball valve 14 and seat 14' constitute the lower standing valve of the pump. This valve cage 13 has a solid peripheral wall and said cage also forms an abutment for the upper end of a coil spring 15 which surrounds the tube 11, the spring 15 having its lower end resting

against the seat member 10 so as to tend to hold said seat member 10 tightly in place in the seat member 8.

The upper end of the valve cage 13 is 5 screw-threaded or otherwise connected to the lower end of an upper conduit tube 16 which is screw-threaded or otherwise fastened at its upper end to a valve cage 17 provided with the usual ball valve 18 and seat 18'.

14 The lower conduit tube 11, the valve cage 13 and the upper conduit tube 16 together constitute the pump conduit and the cage 17, ball valve 18 and seat 18' constitute the upper standing valve of the pump. The valve cage 17 has a sliding fit in a hollow plunger tube 19 which surrounds the conduit tube 16 and which is provided with ports 20. The plunger tube 19 is of greater inside diameter than the outside diameter of the conduit tube 16 to form a space for packing by the liquid being pumped. The valve cage 17 and valve 18 form a stationary piston head in the plunger tube 19. The lower end of said plunger tube 19 is screw-threaded or 25 otherwise fastened to an annular tip 21 which closely and slidably fits the conduit tube 16 so as to form a suitable packing for the lower end of the plunger tube 19 to close the lower end of the annular space between 30 the conduit tube 16 and plunger tube 19.

The conduit tube 16 is provided with ports 22, said ports being so positioned that when the plunger is at the end of its down stroke the ports 22 will communicate with the interior of the plunger above the tip 21 and when the plunger is raised a short distance the ports 22 will communicate with the space below the plunger.

The upper end of the plunger tube 19 is 40 screw-threaded or otherwise connected to a valve cage 23, the peripheral wall of which is solid as clearly shown in Fig. 5. The valve cage 23 is provided with the usual ball valve 24 and seat 24'. The cage 23, ball 45 valve 24 and seat 24' constitute the lower plunger valve. The upper end of the valve cage 23 is screw-threaded or otherwise connected to an upper plunger tube 25 which is of smaller diameter than the lower plunger tube 19 and which is screw-threaded or otherwise connected at its upper end to a valve cage 26, the peripheral wall of said valve cage being solid as clearly shown in Fig. 8. The lower plunger tube 19, valve 50 cage 23 and upper plunger tube 25 together form the pump plunger. The valve cage 26 is provided with the usual ball valve 27 and seat 27' and the cage 26, ball valve 27, and seat 27' constitute the upper plunger valve 55 of the pump.

Surrounding and closely fitting the upper plunger tube 25 is a guide in the form of a liquid-tight sealing barrel 28 which is provided with an external downwardly and inwardly tapered seat 29 to fit a downwardly

and inwardly tapered seat 30 of a tubular seat member 31. The seat member 31 is provided at its lower end with guides in the form of peripherally extending lugs 32, and near its upper end the seat member 31 is 70 provided with a shoulder 33 which is screw-threaded to engage the upper end of a tubular reservoir 34 that is provided with ports 35 just below the level of the seat member 31. Just beneath the shoulder 33 the reservoir 34 is provided with a gas vent or vents 36 through which gas can escape from the reservoir 34 as said gas collects in the upper portion thereof. The ports 36 preferably extend aslant upwardly and outwardly. 80

The reservoir 34 is screw-threaded or otherwise connected at its lower end to a nipple-forming portion 48 of the lower end of a working barrel 37, the upper end of which, in this instance, is substantially on a 85 level with the valve cage 17. The plunger tube 19 slidably fits in the working barrel 37. The lower end of the working barrel 37 forms a liquid admission chamber 38 which is provided with ports 39, said admission 90 chamber extending substantially from the valve cage 13 to the seat member 8 to which the working barrel is screw-threaded or otherwise connected at its lower end. The working barrel 37 is of less outside diameter 95 than the inside diameter of the reservoir 34 so that liquid entering the ports 35 can pass downwardly through the reservoir and around the working barrel to the ports 39. The upper end of the working barrel 37 may 100 be provided with guides in the form of radially extending lugs 37' to hold the upper end of the working barrel central of the reservoir 34.

The parts thus far described constitute the 105 pump, and the seat member 31 is adapted to be connected at its upper end by a coupling 40 to the pump tubing indicated at 41. The valve cage 26 is provided with a screw-threaded pin 42 for connection with the 110 usual sucker line or rod, not shown.

The pump operates as follows: Assuming that the plunger is at the end of its down stroke and that the valves are all closed as shown in the drawings, the plunger will be 115 moved upwardly on its suction stroke and will therefore tend to create a partial vacuum in that portion of the barrel 37 below the plunger. As the plunger tip 21 rises it uncovers the ports 22 so that the suction effect will also take place in the conduit 16 and thus cause the ball valve 14 to open. The oil, or other liquid, which has flowed into the chamber 38 through the perforations 39, as above described, will flow 125 through the ports 12 into the tube 11, thence upwardly through the valve cage 13 into the conduit 16. This upward movement of the plunger also causes a suction effect in the plunger tube 19 above the valve 18 and con- 130

sequently the valve 18 will open so as to allow the oil or other liquid to flow upwardly from the conduit 16 through the valve cage 17 into the plunger tube 19.

5 It will be noted that on the upward stroke of the plunger, as soon as the ports 20 pass the valve cage 17, liquid and gas will flow from the reservoir 34 through the ports 20 into the plunger tube 19 to relieve the 10 partial vacuum and the liquid thus admitted to the tube 19 closes the valve 18 and at the same time will displace any gases which have collected in the tube 19 from said tube 19, said displaced gases opening the valve 24 15 and flowing into the tube 25. Thus the tube 25 together with the valve cages 23, 26 and valves 24, 27 constitute the valved gas trap of the plunger. Liquid in the tube 19 also passes the valve 24 and rises in the tube 25 to 20 the level of the ports 35 thus forcing the gases past the valve 27 so that said gases can flow upward in the pump tubing while the plunger is making its suction stroke.

The inflow of oil into the pump takes 25 place until the plunger reaches the end of its up stroke. The plunger now starts on its down stroke and the pressure exerted by the liquid in the plunger tube 19 on the valve 18 will maintain the valve 18 in closed position and will cause the valve 24 to open to 30 allow liquid to flow from the plunger tube 19 through the valve cage 23 into the upper plunger tube 25. The pressure of the liquid in the tube 25 will raise the valve 27 and 35 consequently said liquid will flow from the tube 25 through the valve cage 26 into the pump tubing 41 and thence to the surface of the earth where it discharges in a manner well understood in the pumping art. 40 When the plunger reaches the end of its down stroke it again starts on its up stroke and the above described operations are repeated as long as the plunger is reciprocated.

45 During the pumping of oil gases that flow into the well with the oil tend to seek escape through the pump and ordinarily cause inefficient working of the pump since they tend to hold the pump valves open and 50 thus cause leakage of not only gas but oil past the valves of the plunger when said valves should be in closed position. By the construction above described the upper plunger tube 25 forms a gas chamber into which 55 the gas can flow from the plunger tube 19 so that on the up or suction stroke of the plunger the pump will be relieved of gases which otherwise would prevent closing of the valve 18 on the down stroke of the plunger since the gases would tend to keep the liquid away from the valve.

On the down stroke of the sucker rods, the plunger with its lower valve cage will descend freely through the liquid in the reservoir without agitating the liquid therein and

without causing any strain on the sucker rods and plunger. On this down stroke the column of liquid in the plunger and conduit remains stationary and the plunger telescopes over the conduit and the liquid passes 70 the valve 24 and fills the tube 25. The valve 27 remains closed, being so held by the column of liquid on top of it.

The instant the up stroke of the plunger begins, the standing valves will open and 75 the space between the valves 24 and 14 gradually increases and into this space the liquid will flow from the reservoir so as to be delivered into the space between the standing valve 14 and plunger valve 24. At 80 the moment the down stroke of the plunger begins, the standing valves close, thus overcoming any tendency to fluctuation in the loading of the upper plunger chamber with liquid. In the pump described the plunger 85 works through a liquid-tight sealing barrel slidably engaging the plunger between the plunger valve cages, thus preventing the back flow of liquid to the reservoir below the pump tubing. The gases in the liquid 90 in the reservoir freely escape therefrom and therefore will not interfere with proper seating of the valves, but said gases will accumulate between the two plunger valves and, on the down stroke of the plunger, will be 95 forced together with the upwardly moving liquids past the upper plunger valve into the pump tubing; and the liquid will flow freely through the reservoir ports into said reservoir and from thence into the plunger. The 100 liquid thus flowing into the pump will not be violently agitated and emulsified, and hence the plunger can effectively elevate the liquid and will not be merely working against a body of foamy emulsified liquid 105 which would result if the liquid were violently agitated. The working parts of this type of pump are at all times submerged in the ascending liquids, without there being any gas filled spaces, and therefore the 110 valves will operate quicker, and in consequence of this the plunger can be operated at a much higher speed than in those pumps in which gas interferes with the quick closing of the valves.

115 From the foregoing it is clear that the essential elements for producing the result noted are a conduit with at least one standing valve, a tubular plunger fitting the outside of the conduit and working through the liquid body, and receiving and discharge valves for the plunger.

If sand should enter the well with the oil and pass through the ports 39 into the chamber 38, thence into the tube 11 through the 120 ports 12, said sand will settle into the tube 4 of the sand trap.

If, to renew the valves or for any other reason, it becomes desirable to withdraw the conduit and its valves from the well, 130

this may be done by raising the plunger higher than in the normal working stroke of the plunger so as to cause an internal shoulder 43, formed by the upper end of the tip 21, to engage an external shoulder 44 on the conduit, said external shoulder being formed by the lower end of the valve cage 17. Further upward movement of the plunger raises the valve cage 17 and with it the 10 conduit tube 16 so as to lift the valve cage 13 and tube 11. Raising of the tube 11 in this wise causes an external shoulder 45 of said tube to engage the valve seat 10 so as to raise said valve seat against the pressure of the spring 15 out of the seat member 8, the shoulder 45 in this instance being formed by the upper end of the tube 4. This upward movement of the tube 4 pulls the plug 3 from the seat member 1, and sand 20 and liquid which may have passed from the tube 4 through the ports 7 into the tube 5 will discharge from the tube 5 through the seat member 1. In the upward movement of the plunger to thus withdraw the same, 25 an external shoulder 46 on the plunger engages the lower end of the barrel 28 so as to disengage said barrel from the seat member 31 and thus cause said barrel to be elevated with the plunger. The shoulder 46 is 30 formed in this instance, by the upper end of the valve cage 23.

To return the pump plunger and the parts attached thereto to their positions in the well, the plunger with the parts associated therewith is lowered into the well until the seat 10 rests upon the seat 9 of the seat member 8. The plunger will then be lowered farther to cause the plunger tip 21 to strike the valve cage 13 so as to drive said valve 35 cage 13 downwardly and compress the spring 15 sufficiently to allow the plug 3 to engage the seat 2 of the seat member 1. Thus the spring 15 yieldingly holds the seat member 10 within the seat member 8 and permits relative adjustment between the plug 3 and seat member 10 so that when the seat member 10 is securely seated in the seat member 8 the plug 3 will also be tightly seated in the seat member 1. The lower end of the valve 40 cage 26 forms an external shoulder 47 on the plunger 25 so that when the plunger is moved downwardly the shoulder 47 will be brought into engagement with a yielding member in the form of a coil spring 49 resting 45 on the upper end of the barrel 28, in order to force said barrel firmly into the seat member 31.

It is understood that the constructor may omit either the sand trap or the working 50 barrel 37 or both sand trap and working barrel. It is preferable to omit the working barrel in event of the well having an unusually large amount of sand or detritus which would tend to plug up the ports 39. 55 If the working barrel be omitted the liquid

will flow directly from the reservoir through the ports 12 into the tube 11, or, in event of the tube 11 becoming sanded, the liquid will flow into the plunger tube 19 through the ports 20, thence through the ports 22 into the 70 upper conduit tube 16, or, in event of the ports 22 and cage 17 being sanded, the liquid will enter the plunger tube 19 above the valve cage 17, when the plunger is raised to bring the ports 20 above the level of the 75 valve cage 17.

The valve cage 26 is tubular and is provided with stops 50 in its bore to limit upward movement of the ball valve 27. Also the cage 26 is provided at its upper end 80 above the stops 50 with a wedge-shaped or downwardly reduced bridge 51 adapted to connect the cage with a sucker rod, not shown, the pin 42, in this instance, being an integral part of the bridge. By this construction of the valve cage 26 the liquid can readily flow upwardly through the cage when the valve 27 is open and as soon as the plunger starts on its up stroke the liquid above the valve presses downwardly on the 90 top of the valve 27 so as to quickly close the valve 27 onto its seat 27.

The invention is not limited in its broader phases to the exact details of construction described above and shown in the drawings 95 but the invention also includes such changes and modifications as lie within the spirit and scope of the appended claims.

I claim:

1. In a pump, the combination of pump 100 tubing, a tubular seat member at the lower end of the pump tubing, a liquid-tight sealing barrel inserted in the seat member, a plunger slidably fitting in the sealing barrel, said plunger being provided intermediate 105 its ends with a cylindrical valve cage having a valve, a discharge valve cage secured to the upper end of the plunger and provided with a valve, a tubular member connected at its upper end to the seat member and provided adjacent its lower end with a second seat member, a third seat member fitting in the second seat member, a working barrel connected at its lower end to the first tubular member, a standing valve cage 110 mounted in the working barrel above the third seat member and connected thereto and provided with a valve, and a conduit connected with the standing valve cage, the plunger being provided adjacent its lower 115 end with a tubular member of less internal diameter than the plunger and fitting the conduit.

2. In a pump, the combination of a conduit tube, a plunger comprising an upper 125 plunger tube, a valve for the upper plunger tube, a valve cage connected with the lower end of the upper plunger tube, a valve for the cage, and a lower plunger tube connected at its upper end with the valve cage 130

and having a tip at its lower end fitting the outside of the conduit tube, there being ports in the lower plunger tube.

3. In a pump, the combination of a conduit tube, a plunger comprising an upper plunger tube, a valve for the upper plunger tube, a valve cage connected with the lower end of the upper plunger tube, a valve for the cage, and a lower plunger tube of larger

10 diameter than the upper plunger tube connected at its upper end with the valve cage and having a tip at its lower end fitting the outside of the conduit tube, there being ports in the lower plunger tube.

15 4. In a pump, the combination of a conduit, upper and lower standing valves for the conduit, a tubular plunger surrounding the conduit, and a valve for the plunger, said plunger having ports adapted to admit fluid 20 to the bore of the plunger above the upper standing valve when the plunger is on its up stroke.

5. In a pump, the combination of a conduit, upper and lower standing valves for 25 the conduit, a tubular plunger surrounding the conduit, and upper and lower valves for the plunger, said plunger having ports adapted to admit fluid to the bore of the plunger above the upper standing valve 30 when the plunger is on its up stroke.

6. In a pump, the combination of a conduit, a valve for the lower end of the conduit, a valve for the upper end of the conduit, a tubular plunger surrounding the 35 conduit, a valve intermediate of the ends of the plunger, a second valve at the upper end of the plunger, and a barrel to guide the plunger adapted to be connected with pump tubing.

40 7. In a pump, the combination of a conduit, upper and lower standing valves for the conduit, a tubular plunger surrounding the conduit, a valve for the plunger, said plunger having ports adapted to admit fluid 45 to the bore of the plunger above the upper standing valve when the plunger is on its up stroke, and a reservoir surrounding the plunger and provided with ports in its upper portion.

50 8. In a pump, the combination of a conduit, upper and lower standing valves for the conduit, there being ports in the conduit between the upper and lower valves, a tubular plunger surrounding the conduit, and a valve for the plunger, said plunger having 55 ports adapted to admit fluid to the bore of the plunger above the upper standing valve when the plunger is on its up stroke.

9. In a pump, the combination of a seat 60 member, a reservoir connected with the seat member, a seat member connected with the upper end of the reservoir, a conduit, a plug connected with the conduit and fitting the first named seat member, a barrel seated in 65 the second seat member, upper and lower

standing valves for the conduit, a plunger slidably fitting in the barrel and having its lower end slidably engaging the conduit, and upper and lower valves for the plunger, there being ports in the plunger and there 70 being ports in the reservoir above the plunger ports.

10. In a pump, the combination of a conduit, upper and lower standing valves for the conduit, a working barrel, a seat member 75 on the lower end of the working barrel, a seat member connected with the conduit and engaging the first named seat member, a tubular plunger slidably fitting in the barrel, and a valve for the plunger, said plunger 80 having ports adapted to admit fluid to the bore of the plunger above the upper standing valve when the plunger is on its up stroke.

11. In a pump, the combination of a seat 85 member, a reservoir connected with the seat member, a seat member connected with the upper end of the reservoir, a conduit, a plug connected with the conduit and fitting the first named seat member, a barrel seated in 90 the second seat member, upper and lower standing valves for the conduit, a working barrel connected with the lower end of the reservoir, a plunger slidably fitting in the working barrel and having its lower end 95 slidably engaging the conduit, and upper and lower valves for the plunger, there being ports in the plunger and there being ports in the reservoir above the plunger ports.

100 12. In a pump, the combination of a seat member, an outer sand trap tube connected with the seat member, a plug to fit the seat member, another sand trap tube inside of the outer tube connected with the plug, a second seat member connected with the upper end of the outer tube, a conduit tube connected with the inner sand trap tube and having ports, an annular seat member slidably fitting the outside of the conduit tube and fitting in the second named seat member, a valve cage connected with the upper end of the conduit tube, a valve for the cage, and a coil spring between the cage and third named seat member.

115 13. In a pump, the combination of a seat member, an outer sand trap tube connected with the seat member, a plug to fit the seat member, another sand trap tube inside of the outer tube connected with the plug, a second seat member connected to the upper end of the outer tube, a conduit tube connected with the inner sand trap tube and having ports, an annular seat member slidably fitting the outside of the conduit tube and fitting in the second named seat member, a valve cage connected with the upper end of the conduit tube, a valve for the cage, a coil spring between the cage and third named seat member, and a reservoir sur-

rounding the conduit tube and connected with the second named seat member and provided with a port.

14. In a pump, the combination of a seat member, an outer sand trap tube connected with the seat member, a plug to fit the seat member, another sand trap tube inside of the outer tube connected with the plug, a second seat member connected with the upper end 10 of the outer tube, a conduit tube connected with the inner sand trap tube and having ports, an annular seat member slidably fitting the outside of the conduit tube and fitting in the second named seat member, a valve cage connected with the upper end of the conduit tube, a valve for the cage, a coil spring between the cage and third named seat member, a barrel mounted in the upper end of the reservoir, and a plunger slidably 20 fitting in the barrel.

15. In a pump, the combination of a seat member, an outer sand trap tube connected with the seat member, a plug to fit the seat member, another sand trap tube inside of the outer tube connected with the plug, a second seat member connected with the upper end of the outer tube, a conduit tube connected with the inner sand trap tube and having ports, an annular seat member slidably fitting the outside of the conduit tube and fitting in the second named seat member, a working barrel connected with the second named seat member and having ports, a valve cage connected with the upper end of the conduit tube and fitting in the working barrel, a valve for the cage, a coil spring between the cage and third named seat member, a reservoir connected at its lower end with the working barrel and provided with 30 ports, and a plunger slidably fitting in the working barrel.

16. In a pump, the combination of a seat member, an outer sand trap tube connected with the seat member, a plug to fit the seat member, another sand trap tube inside of the outer tube connected with the plug, a second seat member connected with the upper end of the outer tube, a conduit tube connected with the inner sand trap tube and having ports, an annular seat member slidably fitting the outside of the conduit tube and fitting in the second named seat member, a working barrel connected with the second named seat member and having ports, a valve cage connected with the upper end of the conduit tube and fitting in the working barrel, a valve for the cage, a coil spring between the cage and third named seat member, a reservoir connected at its lower end 50 with the working barrel and provided with ports, a barrel mounted in the upper end of the reservoir, and a plunger slidably fitting in the working barrel and second named barrel.

17. In a pump, the combination of a reser-

voir having ports, a seat member connected with the upper end of the reservoir and provided with an upwardly and outwardly tapered seat, a seat member connected with the lower end of the reservoir, a barrel having 70 a seat fitting the first named seat, a plunger slidably fitting in the barrel, a standing valve inside of the reservoir, a seat member fitting in the second named seat member, and means connecting the third named seat member with the standing valve and admitting fluid to the standing valve.

18. In a pump, the combination of a reservoir having ports, a seat member connected with the upper end of the reservoir and provided with an upwardly and outwardly tapered seat, a seat member connected with the lower end of the reservoir, a barrel having 80 a seat fitting the first named seat, a plunger slidably fitting in the barrel, a standing valve inside of the reservoir, a seat member fitting in the second named seat member, means connecting the third named seat member with the standing valve and admitting fluid to the standing valve, and 90 a coil spring at the upper end of the barrel between the plunger and first named seat member to frictionally engage the first named seat member.

19. In a pump, the combination of a perforated reservoir, a liquid-tight sealing barrel in said reservoir, a hollow plunger slidably fitting inside of the sealing barrel, a discharge valve cage secured to the upper end of the plunger, the plunger being sufficiently long so that the discharge valve cage is above the sealing barrel when the plunger is at the lower end of its down stroke, a valve for said valve cage, a receiving valve cage for the plunger below the sealing barrel to cause the liquid to move upwardly from below the receiving valve cage to above said valve on the downward stroke of the plunger, and a valve for the receiving valve cage.

20. In a pump, the combination of a liquid-tight sealing barrel, a plunger slidably fitting in the sealing barrel, a discharge valve cage secured to the plunger and adapted to be positioned above the sealing barrel 115 when the plunger is at the lower end of its down stroke, a receiving valve cage for the plunger, the portion of the plunger below the receiving valve cage being of larger diameter than the portion of the plunger above 120 said valve cage to carry liquid to the receiving valve cage, and means outside of the plunger to deliver liquid to the enlarged portion of the plunger.

21. In a pump, the combination of a seat member, a reservoir connected with said seat member and provided with ports in its upper portion, a plug fitting in the seat member, a valved conduit connected with the plug and provided with ports in its 130

lower portion, a valved tubular plunger slidably engaging the conduit, and means surrounding the plunger to seal the upper end of the reservoir.

- 5 22. In a pump, the combination of a seat member, a working barrel connected with said seat member and provided with ports in its upper portion, a plug fitting in the seat member, a conduit tube having ports 10 in its lower portion and connected with the plug, a standing valve connected with the conduit tube, a reservoir connected at its lower end with the working barrel, a valved tubular plunger slidably fitting in the working 15 barrel, and means surrounding the plunger to seal the upper end of the reservoir.

23. In a pump, the combination of a seat member, means adapted to connect the seat member to pump tubing, a solid plug fitting 20 in the seat member, a reservoir provided with inlet ports, a valved conduit having ports communicating with the reservoir and connected with the plug, and a tubular valved plunger slidably fitting the outside of 25 the conduit, said conduit being provided with an external shoulder and said plunger being provided with an internal shoulder adapted to engage the first named shoulder when the plunger is raised above the end of 30 its normal up stroke.

24. In a pump, the combination of a seat member, an outer tube connected with the seat member, a plug to fit the seat member, a second seat member connected with the upper end of the outer tube, a conduit tube 35 connected with the plug, an annular seat member slidably fitting the outside of the conduit tube and fitting in the second seat member, a coil spring to hold the annular 40 seat member in the second seat member, and an abutment on the conduit tube to engage the upper end of the spring.

25. In a pump, the combination of a seat member, an outer tube connected with the seat member, a plug to fit the seat member, a second seat member connected with the upper end of the outer tube, a conduit tube connected with the plug, an annular seat member slidably fitting the outside of the 50 conduit tube and fitting in the second seat member, a coil spring to hold the annular seat member in the second seat member, an abutment on the conduit tube to engage the upper end of the spring, and a shoulder on 55 the conduit tube adapted to engage the annular seat member when the conduit tube is raised.

26. In a pump, the combination of a seat member adapted to be connected with pump tubing, a barrel detachably seated in the seat member, a tubular valved plunger slidably fitting in the barrel and provided with a shoulder adapted to engage the lower end of the barrel when the plunger is raised 65 above the end of its normal up stroke, a res-

ervoir connected with the barrel and provided with ports below the barrel, a valved conduit extending into the lower portion of the plunger, and means to support the conduit.

70

27. In a pump, the combination of a working barrel having ports in its lower portion, a standing valve mounted in the working barrel above said ports, a reservoir surrounding and spaced from the working 75 barrel and having ports, means closing the lower end of the space between the working barrel and reservoir, and a valved plunger slidably fitting in the working barrel.

28. In a pump, the combination of a 80 working barrel having ports in its lower portion, a standing valve mounted in the working barrel above said ports, a valved plunger slidably fitting in the working barrel, a reservoir surrounding and spaced from 85 the working barrel and provided with ports in its upper portion, and means surrounding the plunger to seal the upper end of the reservoir.

29. In a pump, the combination of a 90 working barrel having ports in its lower portion, a reservoir surrounding the working barrel and having ports, a tube extending into the lower portion of the working barrel and provided with ports below the 95 level of the reservoir ports, a standing valve on said tube above the ports and fitting in the working barrel, and a valved plunger slidably fitting in the working barrel above the standing valve.

100

30. In a pump, the combination of a seat member, a reservoir connected with said seat member and provided with a port in its upper portion, a valved conduit connected with the seat member and provided 105 with a port in its lower portion, a valved tubular plunger slidably engaging the conduit, and means fitting the plunger and sealing the upper end of the reservoir.

31. In a pump, the combination of a seat 110 member, a working barrel connected with said seat member and provided with a port in its upper portion, a conduit tube having ports in its lower portion and connected with the seat member, a standing valve connected with the conduit tube, a reservoir connected at its lower end with the working barrel, a valved tubular plunger slidably fitting in the working barrel, and means surrounding the plunger to seal the upper end 115 of the reservoir.

32. In a pump, the combination of a seat member, means adapted to connect the seat member to pump tubing, a reservoir provided with inlets ports, a valved conduit 120 having ports communicating with the reservoir and connected with the seat member, and a tubular valved plunger slidably fitting the outside of the conduit, said conduit being provided with an external shoulder, 125

130

- and said plunger being provided with an internal shoulder adapted to engage the first named shoulder when the plunger is raised above the end of its normal upstroke.
- 5 33. In a pump, the combination of a seat member, an outer tube connected with the seat member, a second seat member connected with the upper end of the outer tube, a conduit tube connected at its lower end 10 with the first seat member, an annular seat member slidably fitting the outside of the conduit tube and fitting in the second seat member, a coil spring to hold the annular seat member in the second seat member, and 15 an abutment on the conduit tube to engage the upper end of the spring.
34. In a pump, the combination of a seat member, an outer tube connected with the seat member, a second seat member connected with the upper end of the outer tube, a conduit tube connected with the first seat member, an annular seat member slidably fitting the outside of the conduit tube and fitting in the second seat member, a coil 20 spring to hold the annular seat member in the second seat member, an abutment on the conduit tube to engage the upper end of the spring, and a shoulder on the conduit tube adapted to engage the annular seat member, 25 when the conduit tube is raised.
35. In a pump, the combination of a reservoir having a vent near its upper end and having a port below the vent, a working barrel inside of and spaced from the reservoir and provided with a port, a valved plunger in the working barrel, a conduit having a port communicating with the interior of the plunger, and a valve for the conduit.
- 40 36. In a pump, the combination of a reservoir having a vent near its upper end and having a port below the vent, a working barrel inserted in and withdrawable from the reservoir, a valved plunger slidably fitting in the working barrel, a seat member connected with the reservoir, a conduit engaging said member and having a port communicating with the interior of the plunger, and a valve for the conduit.
- 45 37. In a pump, the combination of a reservoir having a port only in its upper portion, an upper barrel inserted in and withdrawable from the reservoir and spaced therefrom, a lower barrel in the reservoir provided with a port and spaced from the upper barrel, means closing the upper end of the space between the upper barrel and reservoir, and a valved plunger slidably fitting in the upper and lower barrels.
- 50 38. In a pump, the combination of a reservoir having a port, a working barrel in the reservoir provided with a port, a standing valve fitting inside of the lower portion of the working barrel above the port in the working barrel, a conduit extending down- 55 wardly from the standing valve and provided with a port communicating with the interior of the working barrel, and a valved plunger slidably fitting in the working barrel.
39. In a pump, the combination of pump tubing, a seat member at the lower end of the tubing, a liquid tight sealing barrel inserted in the seat member, a plunger slidably fitting at its upper portion in the sealing barrel, said plunger being provided intermediate of its ends with a cylindrical valve cage, a valve in the cage, there being ports in the lower portion of the plunger to admit fluid to the plunger below the valve, 60 an upper valve cage on the upper end of the plunger to admit fluid from the plunger to the pump tubing, and a reservoir connected with the seat member and having ports therein and surrounding the sealing barrel.
40. In a pump, the combination of a perforated reservoir, a standing valve cage, a perforated conduit extending downwardly from the standing valve cage, a seat member engaged by the conduit below the perforations, and means outside of the conduit to deliver liquid to the perforations.
41. In a pump, the combination of a perforated reservoir, a standing valve cage, a 95 perforated conduit extending downwardly from the standing valve cage, a seat member engaged by the conduit below the perforations, means outside of the conduit to deliver liquid to the perforations, a valved 100 plunger slidably engaging the conduit, said plunger receiving liquid through the conduit from the standing valve cage, and means to seal the upper end of the reservoir.
42. The combination with pump tubing, 105 of a reservoir and pumping mechanism inside of said reservoir, a liquid-tight sealing barrel, there being a coupling connecting the reservoir to the pump tubing and containing a liquid sealed seat for the barrel, the 110 reservoir having ports only in its upper portion, and the barrel being frictionally secured within the reservoir below the pump tubing.
43. The combination with pump tubing, 115 of a reservoir, pumping mechanism inside of said reservoir, said reservoir having ports only in its upper portions, the pumping mechanism having a conduit at its lower portion, there being valve cages for the conduit and there being ports in the conduit below the lower valve cage, the reservoir ports supplying fluid to the conduit ports below the lower valve cage.
44. In a pump, the combination of a conduit having a standing valve, a tubular plunger fitting the outside of the conduit, and receiving and discharge valves for the plunger.
45. In a pump, the combination of a reser- 130

voir provided only in its upper portion with a port, a conduit inside of the reservoir provided with a port and having a standing valve, a tubular plunger fitting the outside 5 of the conduit, and receiving and discharge valves for the plunger.

46. In a pump, the combination of a liquid-tight sealing barrel, a reservoir connected with said sealing barrel, and provided with a port in its upper portion, a perforated conduit inside of the reservoir, means to close the lower end of the reservoir, and a valved tubular plunger fitting the outside of the conduit and working 15 through the sealing barrel.

47. In a pump, the combination of a liquid-tight sealing barrel, a reservoir connected with said sealing barrel and provided with a port in its upper portion, a perforated conduit inside of the reservoir provided with a standing valve, means to close the lower end of the reservoir, and a valved tubular plunger fitting the outside of the conduit and working through the sealing 25 barrel.

48. In a pump, the combination of a liquid-tight sealing barrel, a tubular seat member to receive the sealing barrel adapted to be connected to pump tubing, a hollow plunger slidably fitting in the sealing barrel, discharge and receiving valve cages secured to the plunger, valves for the cages, a conduit projecting into the plunger, means at the upper end of the conduit fitting the 35 plunger, and an inwardly reduced tubular portion at the lower end of the plunger fitting the conduit.

49. In a pump, the combination of a tubular seat coupling member adapted to be connected to pump tubing, a hollow tubular member connected with said coupling member, a seat member at the lower end of the tubular member, a standing valve cage, a conduit connected with said cage, a seat 45 member fitting the last named seat member and shiftably fitting the outside of the conduit, adapted to be connected with the seat member, and a sealing barrel in the coupling member.

50. In a pump, the combination of a tubular member adapted to be connected to

pump tubing, a plunger within the tubular member, a seat at the lower end of the tubular member, a tubular standing valve cage means connecting the cage with the seat 55 member, sealing means at the top of the tubular member between the plunger and the tubular member, a working barrel fitting the standing valve cage, and a valve in the cage.

51. In a pump, the combination of a tubular coupling member adapted to be connected to pump tubing, a working barrel connected to the coupling member, a tubular plunger inside the tubular coupling member and slidably fitting in the working barrel, 60 receiving and discharge valve cages for the plunger barrel, a standing valve cage for the working barrel, valves in the cages, and a tubular member connecting the coupling member with the working barrel. 70

52. In a pump, the combination of a seat member, a conduit tube, an annular seat member slidably fitting the outside of the conduit tube and fitting in the first seat member, a coil spring to hold the annular 75 seat member in the first seat member, an abutment on the conduit tube to engage the upper end of the spring, and means to connect the first seat member to pump tubing.

53. In a pump, the combination of a seat member, a conduit tube, an annular seat member slidably fitting the outside of the conduit tube and fitting in the first seat member, a coil spring to hold the annular seat member in the first seat member, an 80 abutment on the conduit tube to engage the upper end of the spring, a working barrel connected with the first seat member, a tubular plunger slidably fitting in the working barrel, a valve for the plunger, a tubular 85 member connected with the working barrel, and sealing means at the upper end of the tubular member between said tubular member and the plunger adapted to be connected to pump tubing. 95
